UNITED STATES PATENT OFFICE

ALBERT TUCKER AND JAMES S. VAN AUSDAL, OF PENSACOLA, FLORIDA

AIRPLANE

Application filed February 4, 1927. Serial No. 165,962.

Our invention relates to airplanes.

It is the object of our invention to provide means for controlling the equilateral equilibrium of airplanes and it is our further object to provide means for further controlling the landing speed and operation of the airplane through landing.

In particular it is our object to provide means for controlling the negative lift on the superior surface of an airplane wing and to correct the lateral balance of an airplane by controlling this negative lift, such as by breaking the suction through allowing the air to enter the wing from the under side, to collect the air to facilitate its entrance and to arrange for its exit through the upper side of the wing in order to control the suction thereon.

It is our object to eliminate all ailerons, thus securing a reduction in cost of manufacture of an airplane, to eliminate resistance in banking and to provide means of so controlling our mechanism that the lift on the upper wings can be largely reduced during landing to prevent the plane from rolling too far after the ground it touched.

It is a further object of our invention to provide means of controlling a mechanism for effecting the above objects which permits of movement in one direction for effecting the control of such mechanism and movement in the other direction without disturbing the mechanism.

In the accompanying drawings:

Figure 1 is a side elevation of an airplane with our invention installed thereon, the fuselage and struts being partially broken away to show the general arrangement of the control;

Figure 2 is a plan view thereof;

Figure 3 is a section on the line 3—3 of Figure 1 looking in the direction of the arrows;

Figure 4 is a section on the line 4—4 of Figure 3 looking in the direction of the arrows;

Figure 5 is a section on the line 5—5 of Figure 3 looking in the direction of the arrows;

Figure 6 is a detail view of the control cam disk;

Figure 7 is a section on the line 7—7 of Figure 5 looking in the direction of the arrows;

Figure 8 is a section on the line 8—8 of Figure 5 looking in the direction of the arrows showing the scoop closed;

Figure 9 is a section on the line 9—9 of Figure 5 with the scoop in open position;

Figure 10 is a similar view with the scoop closed;

Figure 11 is a view similar to Figure 4 showing the modification or the shutter type of scoop;

Figure 12 is a section similar to Figure 5 showing the shutter arrangement;

Figure 13 is a section on the line 13—13 of Fig. 12;

Figure 14 is a section on the line 14—14 of Fig. 12;

Figure 15 is a bottom plan view of the upper wing;

Figure 16 is a section similar to the section in Figure 5 showing a modified form of vent valve;

Figure 17 is a section on the line 17—17 of Figure 16 showing the vent valve closed;

Figure 18 is a similar view showing the vent valve open;

Referring to the drawings in detail, 1 represents a fuselage equipped with a lower wing 2 and an upper wing 3 connected together by the usual struts 4. The fuselage is supported by the landing gear 5. Any type of airplane will be adapted for the reception of our invention and we have simply illustrated a conventional form of airplane for the purposes of illustration.

The upper wing 3 is divided into the usual wing sections consisting of a center section 6 and side sections 7. The center section directly over the fuselage 1 is arranged to support internally of the wing section a control disk shown in detail in Figure 6.

This control disk is designated 8 and is provided with an ear forming an attachment 9 for engagement with the cable 10 and is actuated by the control stick 11 in the fuselage.

This cable may be actuated in any desired mechanical way as by the pulleys 12 in the fuselage and in the upper central wing section.

5 The cam disk itself is of importance. It is provided with cam slots consisting of arcuate portions 13 and straight portions 14 located at an angle to the arcuate slot 13. This cam disk is pivoted in a portion of the frame work 10 constituting the wing structure of the center section as at 15.

It will be apparent that any cam member movement in the cam slot 13 will not be affected materially until it enters the slot 14 15 which proceeds at an angle thereto towards the center of the disk.

Accordingly, we provide a depending cam finger 16 which is connected to a control rod 17 supported in the brackets 18 in the center 20 section of the wing and in brackets 19 supported in the side sections 7 of the wing. The movement of the cam disk of moving the control stick 11 and cables 10 results in the rotation of the disk.

25 This rotation does not affect the lateral position of the rod 17 or its connections until the pin 16 enters the angular slot 14.

The curved portions and straight portions 30 of the slots in the cam disk 8 are so arranged that they will operate the rods 17 alternately so that while one rod is being shifted the other will remain in its stationary position because its pin is in the arcuate portion of the slot and there is no shifting of that pin relative to the center 20 of the cam disk 8.

Each of the rods 17 is connected at 21 to a cable 22 passing around guide rollers 23. Such cable is connected by a crank arm 24 to a scoop 25. The bottom of said scoop forms 40 a portion of the lower wall of the wing structure. The open end of the scoop designated 26 is directed forwardly so that the air flow over the wing will pass into the scoop and into the interior of the wing. This air makes 45 its exit through the top of the wing through the openings designated 27 of which there may be any desired number depending upon the size of the scoop wing structure and other conditions of similar character.

50 Thus, by moving the stick 11 these clips can be opened alternately with the result that the incoming air will serve to break the vacuum on the upper wing surface or negative lift thereon, thus controlling the equilateral equilibrium of the plane.

It is known that 65% of the lift on the 55 surface of an airplane is produced by suction on the upper surface. The lateral balance of the plane is corrected by our mechanism by breaking this suction and by allowing the air to enter the wing from the under side by any desired means which will control the opening in the under side and permitting such air to make its exit through the upper side by any desired means. Obviously, this control may

also extend to the openings in the upper side walls to the openings in the lower side.

By such a method of lateral control we 70 eliminate ailerons, reduce the cost of construction, eliminate resistance in banking and are enabled, as will be hereinafter pointed out, to reduce the landing speed or the extent of running after the plane touches the ground.

This latter object is accomplished by the 75 following mechanism. Over the pilot's head is pivoted a lever designated 28 which is carried on a cross shaft 29 journaled in the brackets 18 and 19. This cross shaft carries a pitman 30 at either end which pitman is connected to a scoop 31 so that by a movement of the lever 28 both scoops can be opened simultaneously effecting the desired result of reducing the speed of the plane. We thus provide a means for the management of the 80 plane in the air by alternate opening of the scoops and the management of the plane on the ground by the simultaneous opening of the scoops.

Referring to Figures 11, 12, 13 and 14 it 90 will be seen that we have provided an alternative form of scoop mechanism. Instead of employing a scoop with a solid bottom, we provide a plurality of slots 32 each of which is progressively larger than the preceding 95 slot from the wing tip to the controlling edge.

These slots are connected together by links 33, the last link being connected to the horn 34 that is connected to the cable 22.

A similar arrangement is made as in the 100 preceding construction for opening a series of slots 35 simultaneously on both sides on the under surface of the upper wing for the purpose of controlling the plane when on the ground.

In Figures 15, 16, 17 and 18 we have provided another form which is advantageous in certain types of installations for controlling the entrance of air through the bottom 110 wing surface of the top wing.

This consists of the lower wing having a plurality of radially disposed fan shaped slots or cutaway portions 36. Fan-like disks are provided on the interior of the plane, such disks being designated 37. These disks are 115 pivotally supported by a central shaft 38 having a collar, such shaft being embraced by a fork 40 carried on the rod 29 which is operated by the lever 28. The rotation of the fan shaped disks 37 for the purpose of opening and closing the openings 36 is effected by an eccentrically located pin 41 that is connected to the shift rod 42 that has the usual depending cam finger 16 operating in the grooves or slots in the cam disk 8.

Thus, the closure member 37 may be both 120 rotated and elevated so that a single member may be utilized for the dual purpose of controlling the equilateral equilibrium in the air and the ground speed.

It will be understood that we desire to comprehend within our invention such modifications as may be necessary to adapt it to varying conditions and uses.

Having thus fully described our invention, what we claim as new and desire to secure by Letters Patent, is:—

1. In combination in an airplane of a supporting wing surface having passageways from the bottom through the top on either side of the center line of said airplane, means for opening and closing said passageways and means for controlling said opening and closing alternately and independent means for controlling the passage of air through said plane surface on both sides simultaneously.

2. In an airplane having a wing and a fuselage, a control means located in the fuselage, a cam disk located in the wing having spaced arcuate slots and communicating inwardly projecting straight slots, shifting means engaging said slots supported in said wing, means for controlling openings in the under side of the wing surface, said wing surface having openings also in the upper side thereof, and means connected with said shifting means for controlling the opening and closing of said openings in the lower surface of the wing, said openings being arranged on opposite sides of the center line of the wing, whereby when the control means moves in one direction one opening on one side of the under surface of the wing will be opened and the other on the other side will remain closed and the movement of the control means in the other direction will produce the opposite result.

3. In an airplane having a wing and a fuselage, a control means located in the fuselage, a cam disk located in the wing having spaced arcuate slots and communicating inwardly projecting straight slots, shifting means engaging said slots supported in said wing, means for controlling openings in the under side of the wing surface, said wing surface having openings also in the upper side thereof, and means connected with said shifting means for controlling the opening and closing of said openings in the lower surface of the wing, said openings being arranged on opposite sides of the center line of the wing, whereby when the control means moves in one direction one opening on one side of the under surface of the wing will be opened and the other on the other side will remain closed and the movement of the control means in the other direction will produce the opposite result.

4. In combination in an airplane of a supporting wing surface having passageways from the bottom through the top on either side of the center line of said airplane, means for opening and closing said passageways and means for controlling said opening and closing alternately and independent means for controlling the passage of air through said plane surface on both sides simultaneously.

wing and downwardly to a point adjacent to the operator.

4. In combination in a plane having a plane surface in a fuselage, a control means located in the fuselage, cables leading therefrom to the wing surface adapted to operate a rotating control disk having oppositely disposed arcuate and inwardly disposed straight slots, rods disposed in said plane surface laterally thereof in opposite directions having depending cam fingers engaging in said respective slots, means to support and guide said rods, cables connected to the respective ends of said rods, scoops adapted to close openings in the lower surface of said plane surface, said plane surface having upper openings adjacent thereto, said scoops being connected to said cables whereby when the control means in the fuselage will move in one direction one scoop will be opened and the other scoop will be opened on the other side.

5. In combination in a plane having a plane surface in a fuselage, a control means located in the fuselage, cables leading therefrom to the wing surface adapted to operate a rotating control disk having oppositely disposed arcuate and inwardly disposed straight slots, rods disposed in said plane surface laterally thereof in opposite directions having depending cam fingers engaging in said respective slots, means to support and guide said rods, cables connected to the respective ends of said rods, scoops adapted to close openings in the lower surface of said plane surface, said plane surface having upper openings adjacent thereto, said scoops being connected to said cables whereby when the control means in the fuselage will move in one direction one scoop will be opened and the other scoop will be opened on the other side, a second rod system located in said plane surface, a control means therefor extending to a point adjacent to the operator, and a second set of scoops located on either side of the plane surface adapted to close openings in the bottom wall thereof whereby the second set of scoops may be operated simultaneously independently of the first mentioned scoops which are alternately operated.

6. In an airplane having a plane surface in the fuselage, said plane surface having openings in the lower side of the plane surface and in the upper side, closure means for the lower openings, disc means having a pair of arcuate slots, each terminating in an angularly arranged straight slot for controlling said closure means alternately, and means for operating said closure means simultaneously.

7. In an airplane, a main plane surface, means on each side of said main plane surface for controlling the passage of air through said surface including a scoop for each side, a disc member adapted to be rotated to operate said scoops one scoop at a time, and a sec-

ond means on each side of said main plane surface adapted to be simultaneously operated to control the passage of air through the plane surface.

5 In testimony whereof we affix our signatures.

ALBERT TUCKER.
JAMES S. VAN AUSDAL.
